UNITED STATES PATENT OFFICE.

DAVID N. SWATZELL, OF BIRMINGHAM, ALABAMA, ASSIGNOR OF ONE-FOURTH TO B. P. COX, ONE-FOURTH TO R. C. ADCOCK, AND ONE-FOURTH TO W. A. SWATZELL, ALL OF BIRMINGHAM, ALABAMA.

MOTOR-DRIVEN HAIR-CLIPPER.

1,352,326.

Specification of Letters Patent.

Patented Sept. 7, 1920.

Application filed July 17, 1919. Serial No. 311,580.

To all whom it may concern:

Be it known that I, DAVID N. SWATZELL, a citizen of the United States of America, residing at Birmingham, in the county of Jefferson and State of Alabama, have invented certain new and useful Improvements in Motor-Driven Hair-Clippers, of which the following is a specification.

My invention relates to motor driven barbers' hair clippers.

One object of my invention is to avoid the disadvantages incident to a speed reducing drive in the clippers or clipper handle by placing the speed reducing gearing between the motor and the flexible driving shaft so that the latter turns at a slow operating speed and therefore with less vibration and resultant wear.

A further object is to simplify the transmission drive from the flexible shaft to the movable clipper element and to this end my invention contemplates disposing the driving element at right angles to the plane in which the movable clipper element reciprocates, this arrangement enabling me to greatly simplify the drive and to reduce the size, number and cost of parts.

A further object of my invention is to provide a novel type of transmission slide to work between a motor driven crank in the clipper and the reciprocating clipper blade, this slide being especially designed for simplicity in construction and for the inexpensive manner in which it can be assembled in the clipper and guided in its travel.

My invention also comprises the novel details of construction and arrangements of parts, which in their preferred embodiment only are illustrated in the drawings, and in which:

Figure 1 illustrates the clipper apparatus complete with the casing for the motor drive broken away.

Fig. 2 is a cross sectional view enlarged and taken through the clipper on the line 2-2 of Fig. 3.

Figs. 3 and 4 are vertical cross sectional views taken on the lines 3-3 and 4-4, respectively, of Fig. 2.

Similar reference numerals refer to similar parts throughout the drawings.

In the embodiment of my invention illus-

trated, I show any suitable type of electric motor 1 suspended overhead by a bail 2 and hanger hook 3 to any suitable overhead support. The main driving shaft 4 of the motor is provided with a worm gear 5 which drives a worm wheel 6 on the shaft 7 which is coupled to the flexible driving shaft 8. This flexible driving shaft at its free end is provided with a coupling element 9 which is adapted to enter a sleeve 10 and then to couple to a crank shaft 11 that is journaled in the clipper. The ends of the elements 9 and 11 are flattened to form complementary clutch elements. The sleeve is screwed into a socket in the overhung top extension 12 of the main clipper frame 13, a transverse recess 14 (see Fig. 4) being provided in such frame which has parallel top and bottom walls. The wider bottom wall of the recess is overhung at its center by the extension 12 and a top bearing 15 for the shaft 11 being provided therein at the base of the sleeve socket. A bottom bearing is formed in a bushing 16 inserted in a hole in the base through which the crank shaft is inserted.

The said bottom wall of the recess is counter-bored to receive the lower circular collar of the crank 18 on the shaft, there being a similar collar above the crank which engages the under face of the extension 12. The bottom clipper plate 19 is attached to the bottom of the main clipper frame by screws 20 which have their upper ends turned to form guide pins 21 which project into the recess 14 on each side thereof. The usual upper or movable clipper plate or blade 22 is mounted to slide in the stationary blade 19 which latter carries rigid studs 23 which enter elongated slots 24 in the blade 22 and guide it. This movable blade has a center notch 24a in its rear edge adapted to receive the forward downturned arm 25 of the reciprocating transmission slide 26. This slide has a rearwardly opening central slot 27 for the crank 18 to work in and at each side has alining slots open at their outer ends and adapted to receive the guide pins 21.

The usual cover and presser plate 28 is fitted over the sleeve 10 and is yieldingly pressed down by a coil spring 29 surrounding the sleeve and engaged above by an outer

sleeve 30 screwed onto the sleeve 10. I thus yieldingly press the cover down so that its front edge holds the moving blade down with the proper pressure on the fixed blade.

5 The customary clipper handles 31 are attached to the frame 13 at each side.

In operation, the motor 1, through the worm reducing gears 5 and 6, drives the shaft 8 at as low a speed as will directly 10 drive the moving blade at the proper speed for cutting hair, this direct drive being from the crank 18 to the slide 26 and thence through arm 25 to the blade. This drive will operate without noticeable vibration or 15 friction thus not causing the clippers to become heated. Also but little lubricant is needed in the clippers for the low speed drive and it will not give trouble. The tension on the moving blade 22 can be quickly 20 adjusted by screwing the outer sleeve 30 up or down. The approach of the driving shaft at right angles to the plane of the blades is not inconvenient as such slight pull or drag, as may come from the flexible shaft, will 25 only tend to rock the clipper away from the work in a direction almost in line with the natural tilting out of the clipper in actual use.

I consider it an important feature of my 30 invention that I can incorporate my mechanical drive in the present type of clippers with but little change and by the use of comparatively inexpensive parts.

This invention is not intended to be restricted in scope to the specific embodiments shown, but contemplates such modifications as come within the spirit and scope of the claims.

Having thus described my invention, what 40 I claim as new and desire to secure by Letters Patent, is:—

1. In a barber's hair clipper, a frame, a fixed blade attached thereto by screws having rounded projections above the frame, a 45 reciprocatory slide guided by said screws, a crank shaft adapted to reciprocate said slide, a movable blade reciprocable with said slide,

and a flexible driving shaft for said crank shaft.

2. In a barber's hair clipper, a frame having 50 a transverse recess, a crank shaft journaled in the frame and having its crank working in the recess, a slide movable in the recess, a fixed blade attached to the frame, and a movable blade slidable on the fixed 55 blade and operatively connected to said slide, the fixed blade being attached to the frame by screw pins which project into said recess and form guides for said slide.

3. In a barber's hair clipper, a clipper 60 head, a handle therefor, fixed and movable blades carried by said head, a crank shaft journaled in said head, a driving connection from the crank to said movable blade, a sleeve in which said crank shaft turns, a 65 cover plate over the movable blade, a spring surrounding said sleeve and engaging said plate, and a screw element on said sleeve to regulate the tension in said spring.

4. In a barber's hair clipper, a frame having 70 a transverse recess, a crank shaft journaled in the frame at right angles thereto and having its crank working in the recess, a slide transversely reciprocable by the crank in the recess, guides for the slide, a 75 fixed blade attached to the base of the frame and projecting forwardly thereof, a movable blade laterally reciprocable on the fixed blade, guides for said movable blade, and a forwardly projecting down-turned tongue 80 on said slide which engages and reciprocates the movable blade with the slide.

5. In a barber's hair clipper, a frame, a handle set approximately at 45° to the frame, relatively movable blades on said frame, a 85 transmission element laterally movable in the frame, and a flexible shaft set at approximately 90° to the frame and having a low speed drive directly connected to said transmission element.

In testimony whereof I affix my signature.

DAVID N. SWATZELL.
